UNITED STATES PATENT OFFICE

EARL C. APPLEGATE AND ORVAL SMILEY, OF INDIANAPOLIS, INDIANA; SAID SMILEY
ASSIGNOR, BY MESNE ASSIGNMENTS, OF HIS ONE-HALF TO SAID APPLEGATE.

ELECTRIC TIME-SWITCH.

1,250,758.

Specification of Letters Patent. Patented Dec. 18, 1917.

Application filed April 17, 1916. Serial No. 91,736.

To all whom it may concern:

Be it known that we, EARL CLYDE APPLEGATE and ORVAL SMILEY, citizens of the United States of America, and residents of 5 Indianapolis, in the county of Marion and State of Indiana, have invented certain new and useful Improvements in Electric Time-Switches, of which the following is a specification.

10 This invention relates to improvements in electric time switches and the objects thereof are: First, to afford a device that will automatically break an electrical current at a desired predetermined time accordingly as 15 adjusted; second, to so construct the device that it may be utilized for closing an electrical circuit at a predetermined time accordingly as adjusted; and third, to construct the device so that it will indicate 20 plainly its various stages of progress during its operation.

The objects of the invention are accomplished by the construction illustrated in the accompanying drawings in which:—

25 Figure 1 is a plan view of the device; Fig. 2 is a vertical central section of Fig. 1;

Fig. 3 is a detail view showing a modified form of the plunger stem and escapement 30 valve, the stem being shown partially in section;

Fig. 4 is a horizontal section of the device on the line $\alpha-\alpha$ of Fig. 2;

Fig. 5 is a plan view showing a modified 35 form of the base which is used for closing the electrical circuit; and

Fig. 6 is a view of Fig. 5 in a plane at right angles thereto.

Similar characters of reference indicate 40 corresponding parts throughout the several views and referring now to the same:

(A) is a housing having a glass-plate (B) secured in its top, the latter being held in place by a frame (C) that is secured to the 45 housing. Arranged within the housing, adjacent the plate (B), is a base (D) made of suitable non-conducting material. Within

the lower portion of the housing is a cylinder (E) having therein a plunger (F) that is secured to and moved by a stem (G). The 50 plunger has a spring pressed check-valve (H) adapted for the passage of liquid from the upper end of the cylinder to the lower end, and has also an escapement-valve (J) for regulating the passage of liquid 55 through the plunger from the lower end of the cylinder to the upper end. A coil-spring (K) within the upper end of the cylinder bears downwardly against the plunger and tends to hold it in its lowermost 60 position. An arm (L) is adjustably fixed on the stem (G) its outer end extending into a guide (M) that depends from the bottom of the base (D) and thus the stem is prevented from rotating. 65

An internally threaded hub (N) is loosely mounted upon the stem (G) which is threaded so as to engage the threaded hub, the threads being of steep pitch. The hub (N) is held between two annular series of balls 70 (P) that are confined in corresponding cups (Q), the latter being secured rigidly to the base. An index (R) is rigidly fixed to the hub and is turned thereby as the hub is actuated by the stem (G). Secured upon the 75 upper face of the base in concentric relation with the hub is a contact ring (S) having a recess (S') made in its edge. The index bears upon the upper edge of the ring and forms electrical contact therewith except when positioned at the recess (S'). A 80 stop (R') projects from the base and extends within the path of the index and is adapted to arrest the movement of the index when the latter is moved to the recess. 85

A scale-ring (T) having an outer toothed periphery is movably mounted in the upper face of the base, and a pinion (T') is arranged in the base and in constant mesh with the toothed ring so that as the pinion 90 is rotated the ring will accordingly be moved. The pinion is fixed upon a stud (T'') by means of which it is manipulated.

The scale ring has upon its outer face a

series of characters, 1, 2, 3, etc. equally spaced apart and signifying respectively the customary units of time, and the ring is retained in its location in the base by means of clips (U).

The stem (G) and stud (T') project through the end of the housing and are surmounted respectively by handles (G') and (V) by means of which they may be manipulated from the exterior of the housing. Also a screw-plug (W) is arranged in one wall of the housing in line with the screw (L') that binds the arm (L) upon the stem (G) so that upon the removal of the plug access is gained to the screw (L').

In using the device thus constructed the cylinder (E) is filled with liquid such as oil, and connection of the device is made with the lighting or other electric circuit the bolts (Y) and (Z) being used as terminals for the respective ends of the wire (not shown) that forms one of the two branches of the electric circuit. The bolt (Z) has connection with the ring (S) and the bolt (Y) is electrically connected with the index (R) through the medium of the upper cup (P). It will therefore appear that when the index bears upon the ring (S) the electrical circuit will be closed and when the index is positioned at the recess (S') the circuit will be open. The ring is then set with the hour, at which time it is desired to break the circuit, positioned at the index when at the recess, and the stem (G) is then pulled out until the index reaches the hour that designates the present time. The index bearing against the ring (S) completes the circuit so that the current may flow through the device. The action of the spring (K) forces the plunger against the fluid that is trapped in the bottom of the cylinder, and as the oil oozes past the escapement-valve and enters the top of the cylinder, the plunger gradually retracts accordingly drawing the stem in its movement. Thus the index is gradually moved back to its normal position at the recess whereupon the electric circuit is broken. When thus operated one or more electric lamps may be lighted and kept burning until the predetermined time arrives at which time they become extinguished through the operation of the device.

Should it be desired to use the device for turning on the lights at a predetermined time instead of extinguishing them as in the former instance, the form of base shown in Fig. 5 is employed. In this instance two contact points (Z') are arranged in the base (D') and are intended for contact with the index when the latter reaches the stop (R'') so that the electrical circuit when connected with the two contact points be-

comes completed by the index. In this form the operation is similar to the first instance but with the concluding result of closing the open circuit instead of opening a closed circuit.

The velocity with which the device operates is dependent upon the adjustment of the escapement-valve (J) which controls the back-flow of liquid through the plunger. Should it be desired to adjust the escapement-valve from the exterior of the device the modified construction shown in Fig. 3 may be employed. In this form the stem (G') is tubular and has therein an elongated valve (J'), its upper end extending up through the handle and its lower end bearing against the valve-seat (J'') in the tubular stem. Lateral ports (I) are made in the walls of the stem at points adjacent the valve-seat so that the liquid may pass up through the lower end of the stem and become discharged from the ports as it is admitted by the valve.

What we claim is:—

1. In a device of the class described, a housing, a base fixed thereon, a cylinder within the housing, a spring-pressed plunger in the cylinder having a threaded stem extending through the base and top of the housing and having also check and escapement valves for the passage therethrough of fluid from one end of the cylinder to the other, a hub having threaded relation with the stem and being rotatively mounted in connection with the base, an index fixed to the hub, means for preventing the stem from rotating, an electrical contact member on the base adapted for engagement with the index, and an adjustable circular scale on the base in concentric relation with the stem.

2. In a device of the class described, a base, a closed cylinder arranged adjacent the base, a spring pressed reciprocating plunger in the cylinder having a threaded stem extending through the base, and having also check and escapement valves for the passage therefrom of fluid from one end of the cylinder to the other, a hub having threaded relation with the stem and being rotatively mounted in the base and having an index extending therefrom, means for holding the stem from rotating, and contact means upon the base for engagement with the index.

3. In a device of the class described, a housing having a base fixed thereon, a cylinder within the housing, a spring pressed plunger in the cylinder having a stem extending through the base to the exterior of the housing, a check-valve in the plunger for the passage therethrough of fluid from one end of the cylinder to

the other; an adjustable escapement valve adapted to regulate the return flow of said fluid through the plunger, a rotatable index, a quick acting thread upon the stem of said 5 plunger, a hub adapted to be rotated by said quick acting thread to actuate said rotatable index which is rigidly attached to said hub, electrical means adapted to make and break contact with the index at fixed 10 stages of the latter respectively, and an

adjustable scale on the base adjacent the index.

In testimony whereof we affix our signatures, in presence of two witnesses.

EARL C. APPLEGATE.
ORVALL SMILEY.
